[57] **CLAIM**

The ornamental design for a variable dose, reloadable auto-injector, as shown and described.

DESCRIPTION

FIG. 1 is a perspective view of a variable dose reloadable auto-injector showing our new design from the top, rear and right side;

FIG. 2 is a left side elevational view thereof;

FIG. 3 is a top plan view thereof;

FIG. 4 is a front end elevational view thereof;

FIG. 5 is a rear end elevational view thereof;

FIG. 6 is a bottom plan view thereof;

FIG. 7 is a perspective view thereof from the top, rear and right side showing the activator access compartment in the open position thereof; and,

FIG. 8 is a front elevational view thereof showing the needle protector cap thereof in the open position thereof.
